UNITED STATES PATENT OFFICE.

JAMES GAYLE, OF CARROLLTON, KENTUCKY.

DESIGN FOR A RAILROAD BULLETIN-BOARD.

50,147.

Specification for Design.

Patented Jan. 9, 1917.

Application filed October 9, 1916. Serial No. 124,732. Term of patent 7 years.

To all whom it may concern:

Be it known that I, JAMES GAYLE, a citizen of the United States, residing at Carrollton, in the county of Carroll and State of Kentucky, have invented a new, original, and ornamental Design for Railroad Bulletin-Boards, of which the following is a specification, reference being had to the accompanying drawing, forming part thereof.

The figure is a front elevation of a railroad bulletin board showing my new design.

I claim:—

The ornamental design for a railroad bulletin board, as shown.

JAMES GAYLE.

Witnesses:

R. J. WILSON,
C. C. LANCASTER.
